UNITED STATES PATENT OFFICE.

JOHN B. BARTHOLOMEW, OF PEORIA, ILLINOIS, ASSIGNOR TO AVERY COMPANY, OF PEORIA, ILLINOIS, A CORPORATION OF ILLINOIS.

GANG-PLOW.

1,160,686.

Specification of Letters Patent. Patented Nov. 16, 1915.

Original application filed November 29, 1910, Serial No. 594,727. Divided and this application filed July 2, 1912. Serial No. 707,255.

To all whom it may concern:

Be it known that I, JOHN B. BARTHOLOMEW, a citizen of the United States, residing at Peoria, in the county of Peoria and State 5 of Illinois, have invented certain new and useful Improvements in Gang-Plows, of which the following is a specification, reference being had therein to the accompanying drawings.

10 This invention relates to engine drawn plows. In this class of mechanisms each apparatus comprises an engine or tractor, and a draft frame trailing behind it and flexibly connected thereto, this frame being so 15 mounted and supported in relation to the ground surface that the plowbeam-attaching points will be held in substantially fixed positions in relation to the ground surface when the apparatus is at work. Each plow 20 unit is secured to the draft frame in such way that the important parts of the unit, such as the body and the beam, will be so held at all times that they can vibrate vertically in arcs which are fixed in relation to 25 the connecting points on the frame. The plowing mechanisms of the class referred to are in contradistinction to those of the class in which there were several points of flexible union between the beam and the frame; 30 there always being an overhanging support connected to the unit at a point near the plow body, and intended to lift or lower the body, and there generally being also a link system interposed between the front end of 35 the beam proper and the draft frame, the link or links being connected to the front end of the beams by one set of pivot devices, and the front end of the link or links being 40 connected by another set of pivot devices, the front end of the beam proper being allowed to move vertically bodily in relation to the frame and sometimes to move laterally.

In a plow of the sort to which the present 45 invention relates, the plow unit comprises a beam which, when at work, is rigid in relation to the plow body, and is secured to the draft frame by a device furnishing a single pivot abutment around which the beam and the body swing vertically, as aforesaid, in 50 fixed arcs, and the supporting of the body at any one of its several working lines (optionally predetermined) and its lifting vertically to points above the ground are ac-

complished by means of a wheel connected 55 to the beam and located relatively near the body whereby it is adapted to take the down pressure from the suction of the body when at work and from its gravity when it is elevated for transportation. 60

The object of the invention is to provide in a plow of the class set forth means whereby the plowing unit can be lifted in a fixed arc about the aforesaid single pivot abutment by means of power transmitted directly 65 from a ground wheel and applied to effect relative movement between the unit and the ground wheel thereof.

This application constitutes a division of my co-pending application for gang plows, 70 Serial No. 594,727, filed November 29, 1910.

The form of my invention which I prefer as now advised is shown in the accompanying drawings in which,

Figure 1 is a plan view of a gang plow 75 and the rear end of a tractor to which the plow is connected by draft devices; Fig. 2 is a left side elevation of the same with the exception that only one of the individual plows is shown, the others being omitted to 80 avoid confusion; Fig. 3 is a view similar to Fig. 2, but with the plow raised from the ground; Fig. 4 is a rear elevation of the clutch mechanism which constitutes a part of the power lifting device; Fig. 5 is a vertical section on the line 5—5 of Fig. 4; Fig. 6 is a diagrammatic side view of the lifting cams showing their spaced relation to each other; Fig. 7 is a detail view of the upper part of the shank of one of the individual 90 plows.

Referring in detail to the construction illustrated, 1 designates the main frame of the plow as an entirety. This frame is roughly triangular in outline and consists 95 of a side bar 2 having an oblique forward extension 2^a, an obliquely disposed bar 3 which is connected by a block 4 with the oblique bar 2^a, and an obliquely disposed bar 5 extending from the rear end of the side bar 2 forward to the oblique bar 3. A brace bar 6 extends from the left forward corner of the frame to the oblique bar 5. All of the frame bars are rigidly connected as by rivets or bolts. The frame is supported 100 from the ground by wheels there being a front wheel 7 mounted on a swinging yoke or carrier 8, said carrier having at its front

end a vertical trunnion 9 mounted in the block 4 of the frame. In addition there are wheels 10 and 11 mounted upon a transverse axle 12 which is mounted at one end in a bearing bracket 13 on the frame bar 2 and at its other end in a bearing bracket 14 which is carried by a rearward extension 3^a of the frame bar 3.

In the present construction I have shown 10 a gang made up of four individual plows or plowing units 15, 16, 17, and 18. Each of these units preferably consists of a beam or frame made up of parallel bars 19, 20, between which is bolted the shank or standard 21 which carries the plow body 22. The upper part of the plow shank 21 is preferably formed as shown in Fig. 7, there being a hole through which is passed one of the securing bolts 24, a slot 25 through which 20 the other securing bolt 26 passes.

27 is a spring clip which has a sliding engagement with a shoulder 28 formed on the front of the plow shank and which is held in position by a stud bolt 29 and a coiled 25 spring 30 interposed between the head of said bolt and the clip. The upper end of the clip is formed with a hook 30^a which overlies a cross bolt 31 carried by the plow beam bars 19, 20. The spring pressed clip 30 serves to hold the plow body in its normal upright position when the resistance to the advance of the plow is normal, but when an obstruction such as a rock or the like is struck the abnormal resistance causes the 35 spring clip to give way and permits the plow body to swing downward and rearward about the securing bolt 24. The front ends of the beam bars 19 and 20 are preferably spaced apart as shown in Fig. 1, and 40 pivotally secured to a rod or pin 32 which is carried by brackets 33, 34, which in turn are secured to a bar 35 which is bent as shown to form offsets to receive said brackets. The individual plow thus connected to the main 45 frame is free to swing vertically but is held against swinging laterally and against tipping or winging.

Each plow unit is provided with a gage and lifting wheel 36 which is vertically movable with respect to the unit. In order to permit vertical movement or adjustment, each wheel is mounted upon a standard 37 which is arranged to slide vertically in bracket 38 carried by the beam bar 19. Suitable devices are provided on the beam and connected with the wheel for moving the wheel relatively to the beam and thereby lifting the unit as a whole upon the wheel as a support. Of the mechanism shown 39 is a bell crank or lever fulcrumed at 40 on a bracket 41 and connected at its forward end by a link 42 to the standard 37. A hand screw 43 is mounted in the rear end of the lever 39 so as to bear upon one of the beam bars of the plow. The lever 39 carries

an upright extension 39^a to which is adjustably connected a link 44 that extends forward to actuating devices which are presently to be described.

45 is a coil spring which is secured at one 70 end to the lever extension 39^a and at its other end to one of the plow beam portions.

When the front end of the lever 39 is raised throwing the wheel 36 to its uppermost position, which position is determined 75 by the contact of the screw 43 with the plow beam said wheel serves as a gage wheel. By throwing the front end of the lever 39 downward it will be seen that the wheel 39 is forced downward relative to the plow beam, or to speak more accurately, the plow beam is raised relatively to the wheel and as the wheel rests upon the ground the plow body is thus lifted from the soil.

Each of the individual plows are constructed and arranged as has been described and to provide for the lifting of the plows in succession I provide a suitable power mechanism which, in the preferred form, is actuated by ground wheel traction. The 90 mechanism which I have shown and which I prefer is connected to transmit the power of the main frame ground wheels to the lever 39; but it will be understood that as concerns this feature of my invention there 95 can be variation. As shown a short transverse shaft 46 is mounted in bearing brackets or standards 47 and 48, these brackets being carried by the frame bars 2 and 5 respectively. On this shaft 46 is 100 mounted a clutch mechanism which comprises parts as follows: 49 is a sprocket wheel which is rigid with a serrated wheel 50, the two turning loosely on the shaft 46. Adjacent the wheel 50 is a disk 51 which is 105 keyed to the shaft 46, and 52 is a pawl or dog which is pivoted at 53 to the disk 51. This dog carries at one end a roller 54 which is adapted to be swung into engagement with the teeth of the serrated wheel 110 50. On the other end of the dog 52 is formed a shoulder 52^a having a function which will presently be stated. 55 is a spring interposed between an abutment on the disk 51 and the dog 52, said spring tending to 115 swing the roller 54 into engagement with the teeth of the wheel 50.

The bearing standard 48 carries a pivot pin 56 upon which is mounted a lever 57, the said lever being thus disposed adjacent 120 the disk 51 and movable in fixed relation to the draft frame. The lower end of the lever carries a laterally extending lug 58 which extends across the plane of the disk 51 into the plane of the dog 52. The lower end of 125 the lever 57 is notched to receive the end of a spring 59, the other end of which is adjustably secured to a lug 48^a on the standard 48. The spring 59 draws the lower arm of the lever 57 toward the shaft 46 and presses 130

the lug 58 against the periphery of the disk 51. Normally the lug 58 lies in a notch 51^a formed in the disk 51. The lever 57 has an upward extension 60 to which is connected a cord 61 which can be extended forward to a point where it may conveniently be grasped by a person on the tractor. On the axle 12 directly beneath the sprocket wheel 49 is secured a sprocket wheel 62 and this is connected by means of a sprocket chain 63 to the wheel 49 so that the latter is constantly driven when the axle is turning. The parts are normally in the position shown in Fig. 5, the lug 58 being in engagement with the dog 52 and serving to press said dog against the action of the spring 55 into the position shown so that the roller 54 is entirely out of engagement with the serrated wheel 50. If now the cord 61 is pulled forward the lower arm of the lever 57 is swung rearwardly so as to raise the lug 58 out of the notch 51^a and out of engagement with the dog 52. The dog 52 when freed from the pressure of the lug 58 is swung by the spring 55 to bring the roller 54 into engagement with the serrated wheel 50. The rotation of the latter wheel is then transmitted through the dog 52 to the disk 51 thus causing said disk to turn with the shaft. The pull on the cord having been relieved after the engagement of the clutch, the lower end of lever 57 is again swung forward under the action of the spring 59 so that the lug 58 rides upon the edges of the disk 51 as the latter rotates. As the revolution of the disk 51 nears its end, the shoulder extension 52^a of the dog 52 engages the lug 58 so that the dog begins to swing upon its pivot 53 and then as the notch 51^a of the disk 51 comes opposite the lug 58 the latter is snapped forward, thus causing the dog to be swung to its initial position with the roller 54 entirely out of engagement with the serrated wheel 50. In this manner the movement of the disk 51 and therefore of the shaft 46 is stopped precisely at the end of a single revolution.

64 is a sprocket wheel keyed or otherwise rigidly secured to the shaft 46 and this wheel is connected by means of a sprocket chain 65 to a sprocket wheel 66 which is fast on a transverse shaft 67, this shaft being rotatably supported in bearing standards 68, 69. In the construction shown the diameter of the sprocket wheel 64 is one half that of the wheel 66 and it will be seen therefore that when the shaft 46 is given a single revolution by the action of the clutch mechanism which has been described, the shaft 67 will be given a half revolution.

On the shaft 67 is mounted a series of cams 70, 71, 72 and 73, one of said cams being disposed approximately in line with each of the individual plows. Adjacent each cam is arranged a lever arm 74 which is pivoted at its lower end to a bracket 75 on the main frame. This lever is adjustably connected at its upper end to the front end of the link or rod 44 which at its other end is connected to the plow lifting lever 39. Each of the lever arms 74 carries a roller 76 in a position to bear upon the adjacent cam.

Each of the cams referred to is formed on its forward edge or side with an outwardly and rearwardly curving surface 77 which I shall refer to as the active surface. This surface merges with a neutral circular or cylindrical surface 78, and the rear edge of the cam is substantially radial. All of the cams are formed alike but they are spaced angularly from each other as shown in Fig. 6, the cam 70 which is associated with the forward plow 18 being farthest ahead. The spacing of the cams is determined by the distance one plow is in advance of another and by the diameter of the wheels 10, 11, and the ratios of the gears between the wheel axle 12 and the shaft 46, the spacing being such that the several cams come into action one after another so that the plows are lifted from the ground at points in the same transverse line. It will be seen that when the shaft 67 is rotated the active parts 77 of the cams press against the rollers 76 and cause the lever 74 to swing forward and thus the lifting levers 39 are swung so as to lift the individual plows on their respective gage wheels 36. As the rollers 76 one after another ride outward on the active faces 77 of their respective cams they pass upon the neutral cylindrical surfaces 78 of said cams and are thus automatically held forward so as to hold the plows in their elevated positions. In other words the actuating devices for the plow lifting means are non-overhauling, when said devices have been moved into their positions corresponding to the elevated positions of the plows. Furthermore, the length and relative angular arrangement of the cylindrical surfaces 78 of each of the cams is such that at the end of a half revolution of the shaft 67 the several rollers 76 rest upon the intermediate points of the said cylindrical surfaces 78 of the respective cams with said surfaces extending a substantial distance on either side of the rollers 78; so there is no precise point or dead center at which the cam shaft must be stopped in order to secure the automatic locking action of the actuating devices.

To lower the plows it is only necessary to trip the clutch mechanism thus causing one revolution of the shaft 46 and a half revolution of the shaft 67. During this half revolution of the shaft 67 the neutral faces 78 of the cams are moved one after another, beginning with the cam 70, past their respective rollers 76, thus allowing one after another of the levers 74 to swing rearward under the action of the weight of the plows.

so that one after another of the plows are lowered and enter the ground at points on the same transverse line. The prompt lowering of the plows as soon as the turning of the cams permit is insured by the action of the springs 45.

In the drawings I have indicated diagrammatically the rear end of a tractor having wheels 80, 80, mounted on an axle 81, 10 and having a body or framework 82. The plow frame can be connected to the tractor in any suitable manner, but I prefer to employ crossed chains 83, 83, arranged as shown in Figs. 1 and 2.

15 The operation or handling of the plow will be readily understood from the description which I have given. Arriving at the end of the furrows the engineer or driver of the tractor has only to pull forward on 20 the cord 61 so as to trip the clutch mechanism whereupon the cam shaft 67 is given a half revolution during which the cams are swung forward so as to lift the plows from the ground one after another in the manner 25 described and to sustain them in their elevated positions. The machine having been turned the driver can again lower the plows one after the other by simply pulling on the cord 61 as before, thus again tripping the 30 clutch mechanism and causing a second half revolution of the cam shaft 67 during which the plows are again lowered in succession. By adjusting the connections of the links 44 to the lever arms 74 and 39^a the height to 35 which the plows are lifted can be varied within certain limits. And by adjusting the hand screw 43 the depth of the cut can be varied as has been explained.

It will be seen that the mechanism which 40 I provide embodies more than the mere conception, more or less vaguely entertained, of employing power devices for lifting the plows instead of manually operated devices. I provide means to prevent the movement of 45 the plow body below a certain predetermined depth, that is, prevent its bottom working line from being more than a predetermined distance below the ground contacting line of the wheel 36 and yet permit 50 the power devices, at any instant, to immediately press downward the wheel 36, or, in other words, to raise the plow body in relation to that wheel, it being understood that the vertical movements of these two 55 parts, the wheel and the body, are relative, and therefore the wheel can be described as moving downward in relation to the body, or the body as moving upward in relation to the wheel. In manually actuated or 60 hand-lever mechanisms, the wheel and the body require a lock supplemental to the hand lever proper, which lock will prevent relative movement of either the wheel in both directions or of the body in both directions. In my construction there is a lock or

stop acting in one direction only, that is to say, acting to prevent the body from descending below a predetermined line, or to prevent the wheel from relatively rising above a predetermined line, while the body 70 is at the same time free to move in one direction and the wheels free to move in another direction, and because of this the power mechanism is free to automatically press the wheel downward or lift the body upward. 75 And the final abutment or thrust point around which these relative movements take place is the abutment provided by the single fixed hinge uniting the beam to the draft frame. The train of power transmitting devices is so arranged that their extreme points of action or efficiency are at a predetermined, but fixed, distance; for example, from the roller 76 the distance through the lever 74, the link 44, the arm 39^a and the lever 39 to either 80 the axis at 40 of the latter lever or the thrust point at 42, is a fixed distance (after the parts have been adjusted and set) at all times, and therefore the lifting action in the plow unit is always the same, and the plow 85 body will always be lifted, at any lifting action, to the same height. And it is not desirable to have any other adjustments or movements dependent upon this, or to have this distance dependent upon any other factor 90 in the assemblage of parts, as for instance the line of draft on the plow body. Again, I have provided adjusting means by which the plow body can, at any lifting action, be elevated to a higher or a lower point (when 95 it is at its highest elevation) as may be desired; such adjustment being allowed by the row of pivot receiving apertures in the bar or lever 74 for connecting thereto the link 100 44. When the link is connected to the lever 105 at points relatively distant from the pivotal connection at 75, the rod 44 and the lever 39 will be drawn backward farther and the plow body will be lifted higher upon the wheel, and vice versa. Where the apparatus 110 is being transported over an uneven or broken surface, it is necessary to lift the bodies to higher points in order to have them always clear the ground. Where, however, it is possible to carry them with the 115 plow points nearer to the surface, it is preferable to shorten the vertical distance of the lift so that they will ride more steadily. Again, I provide means for varying the relations of the parts in such way that when it 120 is necessary more power can be exerted by the lever 39 in lifting the body. The link or chain 44 can be connected to the lever 39 at various radial distances. When they are connected at a longer radial distance the motion of the lever 39 at each lifting action will be slightly slower than when the connection is made at a shorter radial distance, but there will be a corresponding increase in 125 power, a matter becoming necessary where 130

heavy soil or tough sod lies above and is pressing down upon the plow body, requiring that the hard soil shall be broken or the sod layer torn loose before the body can escape above the surface.

5 The connecting devices between the lever 74 on the main frame and the lever 39 on the beam can be so connected as to provide some looseness. Such an adjustment is indicated in Figs. 2 and 3 where the link 44 is shown as being pivoted to the lever 74 at the intermediate pivot hole in the lever. This looseness is found sufficient on the one hand to permit the beam to move downward to 10 some extent below its predetermined normal horizontal plane without causing such tension on the lever 39 as to press the wheel 36 down to any material extent, and on the other hand, slack or looseness is not sufficiently great to prevent the power devices from practically immediately exerting tension through the transmitting train to effect an instant pick up of the beam and body on the wheel. A sufficient variation, as required by circumstances, can be insured in 15 this respect by the provision made for varying the point of attachment of the draft train to the lever 39. By ascertaining the proper amount of lost motion and slackness 20 in a draft train such as that herein shown and then attaching the united parts of the train at the proper points a sufficiently wide range in the vertical movements of the plow beams can be provided for, particularly 25 where the land is approximately level throughout to avoid the lifting of the body out of the ground by pressure on the wheel, whether the beam descends to a limited extent from or lies above its normal plane.

30 40 What I claim is:

1. The combination of a draft frame detachably and flexibly connectible with a tractor, ground wheels upon which the frame is supported, a trailing plowing unit having 45 at its front end a vertically fixed transverse horizontal pivotal connection with the frame, a vertically adjustable ground wheel normally carrying the unit in fixed relation to the ground, and a ground wheel actuated 50 power transmitting train connected to move the adjustable ground wheel downward with respect to the unit and thereby lift the unit, the said train having all of its parts connected and mounted in definite predetermined 55 relationship to the draft frame and the unit, whereby the lifting of the unit is definitely and fixedly related to the rotation of the actuating ground wheel.

2. The combination of a draft frame 60 detachably and flexibly connectible with a tractor, ground wheels upon which the frame is supported, a trailing plowing unit having at its front end a vertically fixed transverse horizontal pivotal connection with the 65 frame, a vertically adjustable ground wheel

normally carrying the unit in fixed relation to the ground, and a ground wheel actuated power transmitting train connected to move the adjustable ground wheel downward with respect to the unit and thereby lift the 70 unit, the said train having all of its parts connected and mounted in definite predetermined relationship to the draft frame and the unit, whereby the lifting of the unit is definitely and fixedly related to the rotation 75 of the actuating ground wheel, and the said train comprising a clutch having means for automatically disengaging it after the lifting of the unit.

3. The combination of a draft frame detachably and flexibly connectible with a tractor, ground wheels upon which the frame is supported, a trailing plowing unit having at its front end a vertically fixed transverse horizontal pivotal connection with the frame, a 80 vertically adjustable ground wheel normally carrying the unit in fixed relation to the ground, and a power transmitting train actuated by a ground wheel of the draft frame and connected with the adjustable ground 85 wheel to move it downward with respect to the unit and thereby lift the unit, the said train having all of its parts connected and mounted in definite predetermined relationship to the draft frame and the unit, whereby the lifting of the unit is definitely and fixedly related to the rotation of the said 90 draft frame ground wheel. 95

4. The combination of a draft frame detachably and flexibly connectible with a tractor, ground wheels upon which the frame is supported, a trailing plowing unit having at its front end a vertically fixed transverse horizontal pivotal connection with the frame, a vertically adjustable ground wheel 100 normally carrying the unit in fixed relation to the ground, and a power transmitting train actuated by a ground wheel of the draft frame and connected with the adjustable ground wheel to move it downward 105 with respect to the unit and thereby lift the unit, the said train having all of its parts connected and mounted in definite predetermined relationship to the draft frame and the unit, whereby the lifting of the unit is 110 definitely and fixedly related to the rotation of the said draft frame ground wheel, and the said train comprising a clutch having means for automatically disengaging it 115 after the lifting of the unit. 120

5. The combination of a draft frame detachably and flexibly connectible with a tractor, ground wheels upon which the frame is supported, a trailing plowing unit having at its front end a vertically fixed transverse horizontal pivotal connection with the frame, a vertically adjustable ground wheel normally carrying the unit in fixed relation to the ground, and a ground wheel actuated power transmitting train connected to move 125 130

the adjustable ground wheel downward with respect to the unit and thereby lift the unit, the said train having all of its parts connected and mounted in definite predetermined relationship to the draft frame and the unit, whereby the lifting of the unit is definitely and fixedly related to the rotation of the actuating ground wheel, and the said train being optionally adjustable to vary the extent of movement of the adjustable wheel with respect to the unit.

6. The combination of a draft frame detachably and flexibly connectible with a tractor, ground wheels upon which the frame is supported, a trailing plowing unit having its front end a vertically fixed transverse horizontal pivotal connection with the frame, a vertically adjustable ground wheel normally carrying the unit in fixed relation to the ground, the said ground wheel being freely movable downward with respect to the unit upon the application of power, an adjustable stop for limiting the movement of the ground wheel upward with respect to the unit to determine the depth of plowing, and a ground wheel actuated power transmitting train connected to move the adjustable ground wheel downward with respect to the unit and thereby lift the unit, the said train having all of its parts connected and mounted in definite predetermined relationship to the draft frame and the unit, whereby the lifting of the unit is definitely and fixedly related to the rotation of the actuating ground wheel.

7. The combination of a draft frame detachably and flexibly connected with a tractor, ground wheels upon which the frame is supported, a trailing plowing unit having at its front end a vertically fixed transverse horizontal pivotal connection with the frame, a vertically adjustable ground wheel normally carrying the unit in fixed relation to the ground, the said ground wheel being freely movable downward with respect to the unit upon the application of power, an adjustable stop for limiting the movement of the ground wheel upward with respect to the unit to determine the depth of plowing, and a ground wheel actuated power transmitting train connected to move the adjustable ground wheel downward with respect to the unit and thereby lift the unit, the said train having all of its parts connected and mounted in definite predetermined relationship to the draft frame and the unit, whereby the lifting of the unit is definitely and fixedly related to the rotation of the actuating ground wheel, and the said train being optionally adjustable to vary the extent of movement of the adjustable wheel with respect to the unit.

8. The combination of a draft frame detachably and flexibly connectible with a tractor, ground wheels upon which the

frame is supported, a trailing plowing unit having at its front end a vertically fixed transverse horizontal pivotal connection with the frame, a vertically adjustable ground wheel normally carrying the unit in fixed relation to the ground, and a power transmitting train connecting a ground wheel of the draft frame with the said adjustable ground wheel and comprising an element mounted on the draft frame and movable in fixed relation thereto, the said train serving to move the adjustable ground wheels downward with respect to the unit to lift it.

9. The combination of a draft frame detachably and flexibly connectible with a tractor, ground wheels upon which the frame is supported, a trailing plowing unit having at its front end a vertically fixed transverse horizontal pivotal connection with the frame, a vertically adjustable ground wheel normally carrying the unit in fixed relation to the ground, and a power transmitting train connecting a ground wheel of the draft frame with the said adjustable ground wheel and comprising an element mounted on the draft frame and movable in fixed relation thereto, the said train serving to move the adjustable ground wheels downward with respect to the unit to lift it.

10. The combination of a draft frame detachably and flexibly connectible with a tractor, ground wheels upon which the frame is entirely supported, a trailing plowing unit having at its front end a vertically fixed transverse horizontal pivotal connection with the frame, a vertically adjustable ground wheel normally carrying the unit in fixed relation to the ground, the said ground wheel being freely movable downward with respect to the unit upon the application of power, an adjustable stop for limiting the movement of the ground wheel upward with respect to the unit to determine the depth of plowing, and a power transmitting train connecting the ground wheels of the draft frame with the said adjustable ground wheel to move the latter downward with respect to the unit thereby lifting the said unit and comprising an element mounted on the draft frame and movable in fixed relation thereto.

11. The combination with the plow frame adapted to be flexibly connected to a tractor, of a plow unit having a beam hinged to the frame, a plow body vibrating vertically in fixed arcs, a body supporting wheel fixed against movement in one direction with respect to the body but freely movable rela-

tively thereto in the opposite direction, a power transmitter supported permanently on the beam and movable relatively thereto for moving said wheel relatively to the body, 5 a power mechanism on the draft frame for exerting power on said transmitter on the beam, and a traction wheel connected to the plow frame for actuating the power mechanism.

10 12. The combination with the plow frame adapted to be flexibly connected to a tractor, of a plow unit having a beam hinged to the frame, a plow body vibrating vertically in fixed arcs, a body supporting ground wheel 15 movable freely downward relatively to the body, a two-part power transmitter having one of its parts movably mounted on the beam and pivotally connected to the wheel and having the other part movably mounted 20 on the plow frame and connected with the part on the beam, a power shaft on the plow frame for actuating the said second part of the transmitter, and a traction wheel on the plow frame for actuating the said shaft. 25 13. The combination with the plow frame adapted to be flexibly connected to a tractor, of a plow unit having a beam hinged to the frame, a plow body vibrating vertically in fixed arcs, a supporting wheel movable freely downward relatively to the body, a lever mounted on the beam and pivotally connected to the wheel, an adjustable stop for limiting the motion of the lever in the direction opposite to that necessary to lift 30 the plow and power devices on the plow frame intermittently connected operatively with the said lever.

2% 14. The combination with the plow frame

adapted to be flexibly connected to a tractor, of the plow unit having a beam hinged to 40 the frame, a plow body vibrating vertically in fixed arcs, a body supporting wheel carried by the beam and freely movable relatively to the body in one direction, a stop for limiting the movement of the wheel in 45 the opposite direction, a power transmitter on the plow frame, a power transmitter on the beam pivotally connected to the wheel, a connecting device between the said power transmitters, a power mechanism on the plow 50 frame intermittently connected operatively with the second aforesaid transmitter, and a traction wheel on the plow frame for actuating the power mechanism.

15. The combination of a plow frame 55 mounted in substantially fixed relationship to the ground and adapted to be flexibly connected to a tractor, a plow beam connected to the frame for movement about a fixed transverse axis, the plow body on the beam, 60 a vertically movable ground-engaging wheel adjacent the body, a lever pivoted on the beam and pivotally connected with the ground wheel, a power mechanism on the plow frame, power transmitting devices connected to the power mechanism and adjustably connected to the said lever, and means for varying the movement of the lever relative to the beam.

In testimony whereof, I affix my signature, 70 in presence of two witnesses.

JOHN B. BARTHOLOMEW.

Witnesses:

J. M. CALDWELL,
A. L. GREGORY.
